UNITED STATES PATENT OFFICE.

GEORGE W. LAKE, OF RUMFORD, RHODE ISLAND, ASSIGNOR TO METACOMET CORPORATION, OF RUMFORD, RHODE ISLAND, A CORPORATION OF RHODE ISLAND.

WATER-CHAMBER FOR WATER-HEATING APPARATUS.

1,115,076.

Specification of Letters Patent.

Patented Oct. 27, 1914.

Application filed February 4, 1914. Serial No. 816,652.

To all whom it may concern:

Be it known that I, GEORGE W. LAKE, a citizen of the United States, and resident of Rumford, in the town of East Providence, in the county of Providence and State of Rhode Island, have invented certain new and useful Improvements in Water-Chambers for Water-Heating Apparatus, of which the following is a specification.

10 This invention relates to the construction of a water chamber for water heating apparatus, and has for its object to provide a chamber whose walls are adjacent each other for the purpose of spreading out the water 15 into a thin film or layer whereby it may be quickly heated.

It is found in practice that where this heating chamber is constructed of two separate plates soldered together that the heat 20 from the burner acting upon the lower soldered edge soon melts and destroys the same and causes the chamber to leak. To obviate this difficulty I have formed the chamber of a single piece of sheet metal and 25 folded one portion over and back substantially upon itself, the folded edge being placed at the bottom where it is the hottest without detrimental effect.

A further object of the invention is to 30 corrugate one of the walls of the chamber longitudinally to provide a series of small water receiving tubes and also to render more effective the action of the heat on the walls of the chamber.

35 The invention further consists in bending these double walls into a series of transverse folds to render the body flexible whereby it may readily expand and yield to the action of heat and cold without injury.

40 A further object of the invention is to fold both the upper and lower portions of one of the walls over and back substantially upon itself, the edge of the upper portion being bent upward and the edge of the lower portion being bent downward forming interlocking lips united by solder forming a joint whereby if the solder should melt, instead of running out and spoiling the joint, the solder would be retained within the up-turned 45 lip and as soon as cooled would again and automatically seal the joint.

A still further object of the invention is to provide rivets or stay members through the walls of each fold to prevent them from

separating by action of excessive internal 55 pressure.

With these and other objects in view, the invention consists of certain novel features of construction, as will be more fully described and particularly pointed out in the 60 appended claims.

Of the accompanying drawings: Figure 1 is a sectional side elevation showing my improved heating chamber in position in a portable water heater. Fig. 2 is an end view 65 showing the multiple folds of my improved water heating chamber. Fig. 3 is a face view showing the general form of the sheet plate from which my heating chamber is constructed showing the plurality of longitudinal corrugations in one portion thereof. Fig. 4 is an edge view of the plate showing a portion of one of the folds partially in section. Fig. 5 is an enlarged view illustrating a portion of one of the folds in section showing the joint whereby the two edges are united and the rivet for connecting and supporting the adjacent walls. Fig. 6 is a sectional edge view of one of the folds. Fig. 7 is a detail illustrating the interlocking 70 joint edges of the folded portions of the plate. 80

Referring to the drawings, 10 designates a portable heater more particularly adapted for domestic use, and in which my improved 85 water chamber 11 is mounted above the multiple gas burner 12, preferably of the Bunsen burner type. It is found in practice that where a water chamber of this character is constructed of two separate pieces of 90 sheet metal soldered together, that the lower edge, upon being exposed to the direct heat of the flame soon melts the solder and causes the chamber to leak. To obviate this difficulty I have formed my improved water 95 chamber of a single piece of sheet metal and have provided one of the walls 13 with a series of longitudinal corrugations, the general lay-out of which is best illustrated in Fig. 3. I then fold the lower section 14 upward on the dotted line 15 and the upper section 16 over and downward on the dotted line 17. I then turn upward the upper edge as at 18, see Fig. 7, and also turn downward the lower edge 19, and cause them to interlock one with the other, as illustrated in said figure, the same having been previously 100 tinned or supplied with the requisite amount 105

2. of soldering material. I then roll the folds of this joint together, and upon subjecting the same to the proper amount of heat the solder is caused to flow and firmly unite the 5 parts, as best illustrated at 19 in Fig. 5. This joint thus constructed is preferably located near the upper edge, see Fig. 6, or at a sufficient distance above the lower edge, or position of greatest heat, so as not to be affected and again unsoldered. If, however, by any accident, such as inadvertently shutting off the supply of water, or other cause, an excessive heat should be applied to the water chamber and the solder in this joint 10 should become melted, it could not run out of the trough-shaped groove, but would be retained therein and as soon as the chamber again cooled the joint would be again and automatically sealed. After this joint 15 has been formed the plate, which is now in a tubular form is rolled down flat bringing the plain wall 14 and the corrugated wall nearly together, as illustrated in Figs. 5 and 6, then the stock at the ends 25 and 26 is 20 folded over and inter-locked and permanently joined together by hard solder. This double walled body is then preferably bent into a series of transverse folds, as illustrated in Fig. 2, whereby the chamber is 25 rendered yieldable, to readily expand and contract with the changing temperatures. This folded chamber is set endwise into the casing of the heater by which construction it will be seen that the heat from the burner 30 below passes up between each fold and in contact with both the corrugated wall and the plain wall of each fold throughout the whole length of the same. The corrugations or tubes retaining the water extend outward 35 and have the effect of horizontally disposed ribs which engage and arrest the heat and thereby produce the maximum effect to quickly heat the water passing through the chamber. 40 45 A water inlet pipe 20 is connected to the boss 21 on the lower side of the first fold and a water outlet pipe 22 is connected to the boss 23 on the upper side of the last fold whereby the water enters at the bottom and 50 as it passes back and forth through the different folds is subjected to a prolonged action of the heat, and finally works its way upward through the narrow passageways between the plates and out through the discharge pipe 22. In some cases where the water pressure is heavy it is found desirable to tie the adjacent walls of each fold together to prevent the same from unduly separating by the action of the internal pres-

sure. To accomplish this I preferably insert a rivet 24, see Fig. 5, or other tying member and solder the same in position.

I claim:

1. In a device of the character described, the combination with a water chamber 65 formed of a single piece of sheet metal having one of its walls corrugated longitudinally, the lower portion of the corrugated wall being folded over and back substantially upon itself forming a series of water 70 retaining tubes, means for uniting the meeting edges of the folded portions said double walls being bent into a series of transverse folds, an inlet pipe connected to one end at the bottom and an outlet pipe connected to 75 the opposite end at the top and a burner beneath the lower edge of the chamber.

2. In a water heater, a water chamber comprising a body formed of sheet metal having one of its walls corrugated, both the 80 upper and lower portions of said wall being folded over and back substantially upon itself, means for uniting the meeting edges of said folded portions, said double walls 85 being bent into a series of transverse folds, and said plate being provided with inlet and outlet openings.

3. In a water heater, a water chamber comprising a body formed of sheet metal having one of its walls corrugated, both the 90 upper and lower portions of said wall being folded over and back substantially upon itself, the edge of the upper portion being bent upward and the edge of the lower fold 95 being bent downward forming interlocking lips united by solder, said double walls being bent into a series of transverse folds and said plate being provided with inlet and outlet openings.

4. In a water heater, a water chamber 100 comprising a body formed of a single piece of sheet metal having one of its walls corrugated, the lower portion of said wall being folded over and back substantially upon itself, means for uniting the meeting edges of 105 the folded portions, means for tying together the opposite adjacent walls of said body at intervals, said double walls being bent into a series of transverse folds, and said plate being provided with inlet and 110 outlet openings.

In testimony whereof I affix my signature in presence of two witnesses.

GEORGE W. LAKE.
